(57) **CLAIM**

The ornamental design for a sand dressing implement, as shown.

DESCRIPTION

FIG. 1 is a perspective view depicting a sand dressing implement with rake.

FIG. 2 is a front view depicting the sand dressing implement with rake.

FIG. 3 is a rear view depicting a sand dressing implement with rake.

FIG. 4 is a top view depicting a sand dressing implement with rake.

FIG. 5 is a bottom view depicting a sand dressing implement with rake.

FIG. 6 is a side view depicting the sand dressing implement with rake.

FIG. 7 is a second side view depicting the sand dressing implement with rake.

FIG. 8 is a rear view depicting a sand dressing implement.

FIG. 9 is a front view depicting the sand dressing implement.

FIG. 10 is a rear view depicting a sand dressing implement.

FIG. 11 is a top view a sand dressing implement.

FIG. 12 is a bottom view depicting the sand dressing implement.

FIG. 13 is a side view depicting the sand dressing implement; and,

FIG. 14 is a second side view depicting the sand dressing implement.

The broken lines represent portions of the implement and form no part of the claimed design.

The rake portion is removed from FIGS. 9-14 to show aspects of the design that may not be apparent in other views.
